UNITED STATES PATENT OFFICE.

JOHN MILLS, OF WYOMING, NEW JERSEY, ASSIGNOR TO WESTERN ELECTRIC COMPANY, INCORPORATED, OF NEW YORK, N. Y., A CORPORATION OF NEW YORK.

WAVE-TRANSMISSION CONTROL CIRCUITS.

Application filed December 30, 1922. Serial No. 609,885.

This invention relates to wave transmission systems and more particularly to systems for controlling the transmission of signals in a carrier wave system.

- 6 It has been found that many types of signals transmitted over communication circuits contain or are associated with waves having peaks considerably in excess of the average value of the wave peaks transmitted. 10 For example, voice waves usually contain excessive peaks which occur more or less irregularly from time to time in the course of transmission of said waves, and are not essential to an understanding of the speech. 15 When the peaks in a voice wave are applied to a modulator, the load thereon rises to an excessive value as compared to the normal load. These excessive peaks may also produce excessive loads on any amplifiers which 20 transmit the voice wave to the modulator or that receive the modulated wave therefrom. 25 In a multiplex carrier wave system where several channels, having separated frequency ranges, transmit carrier waves over a common path or medium, an excessive peak transmitted on a carrier wave in one channel may be of sufficient amplitude or power to produce appreciable disturbing current in 30 an unrelated channel even though said channels are ordinarily capable of operating without mutual disturbance when waves of normal amplitude are transmitted there- 35 through. When a repeater common to a plurality of channels in a multiplex system is employed to repeat simultaneously a plurality of signals, the presence of excessive peaks in one carrier wave may result in over-loading the repeater, thereby causing the repeater to distort one or more of the simultaneous signals and to intermodulate the various waves being repeated. This causes cross-talk between the different channels and also produces other disturbances there- 40 in.

45 One object of the present invention is to reduce cross-talk or disturbances in a carrier wave transmission system.

50 Heretofore it has been considered necessary to provide modulators, repeaters and the like of large power output in order to avoid the disturbing effects of excessive peaks in the signal wave. One object of the present invention is to provide methods and means for reducing the size of carrier wave 55 modulator and associated apparatus re-

quired for transmitting a wave of given power without appreciable loss of signal energy and without distortion.

In accordance with the present invention each channel of a multiplex carrier wave system is provided with power limiting means to limit the amplitude of modulating waves transmitted therethrough to a predetermined maximum value, while the un-suppressed portion of said modulating wave 65 is transmitted without appreciable distortion to a modulator in which a carrier wave is modulated in accordance with the unsuppressed portion of said modulating wave. The wave transmitted from said power 70 limiter cannot exceed a fixed maximum value, and the apparatus receiving energy from said power limiter is therefore subject- 75 ed to a smaller and definitely limited load. This apparatus may consequently have a 80 smaller power rating, whereby under normal conditions the modulator and associated repeaters may be operated more efficiently than in the case where apparatus, such as modulators of larger power output, are oper- 85 ated at a power output considerably lower than the maximum.

These and other objects of the invention will be apparent from the following more detailed description when taken in connec- 85 tion with the appended drawing and claims.

In the drawing the figure shows a schematic diagram of connections for a multiplex carrier wave system in which the sub-station 1, labeled S, may include any usual 90 type of transmitting and receiving apparatus adapted for telephony, telegraphy, signaling or the like. Station 1 is connected by a transmission line or circuit 2 to the hybrid coil or balanced transformer con- 95 nection 3 to which is connected the usual form of balancing network 4, labeled N, the east-going channel, labelled E₁, and the west-going channel, labelled W₁. The signal or modulating wave is transmitted to the 100 power limiter 5, labeled PL, which is shown as a relay or amplifier of the space current type of a form well-known in the art. The temperature of the cathode 6 may be var- 105 ied by varying the resistance 7 in series with the energizing source for the cathode 6. It is well-known that by reducing the tem- perature of the cathode 6 to the proper value, a wave impressed upon the power limiter 5 will be repeated with the exception of its 110

peak values. These peak values are suppressed or chopped off and are not transmitted out from the limiter 5. The degree to which the impressed wave is suppressed or is not transmitted depends upon the degree to which the temperature of the cathode 6 is reduced.

It is preferred that the polarizing potential 8 be adjusted so that the limiter 5 operates at the center of its space current characteristic. When a wave of sufficient amplitude is impressed on the power limiter, a positive half of said wave will be transmitted through the limiter with a maximum value equal to that of the negative half wave transmitted therethrough. In practice the power limiter 5 is adjusted by means of the resistance 7 or by other well-known means to transmit without distortion substantially the entire signal wave impressed thereon, the adjustment being such that portions of the signal wave having peaks considerably in excess of the average value of the peaks in said signal wave are suppressed by the power limiting action described above. Any other well-known type of substantially distortionless repeater having a controllable power limiting action, such as described above in connection with the limiter 5, may be employed in place of a repeater of the space current type. The unsuppressed portion of the signal wave is impressed on the modulator 9, labeled M, which is an electric relay having a non-linear transmission characteristic and may be of the type disclosed in U. S. Patent No. 1,350,752 to Van der Bijl, granted August 24, 1920, or of any other well known type. Carrier waves modulated in accordance with the signal or modulating wave are transmitted through the band filter or other selective circuit 10, labeled F, which transmits only those waves which are essential to the intelligible reception of the signal at the receiving station. Filter 10 may be of the type disclosed in U. S. Patent No. 1,227,113 to Campbell, granted May 22, 1917. Waves transmitted through filter 10 are conveyed over the transmitting path 11 common to a plurality of east-going channels E₁, E₂, etc., and to the hybrid connections 12 provided with the usual form of balancing network 13.

Carrier waves are transmitted from the hybrid connections 12 over the transmission line 14 to the two-way repeater 15, labeled R, and from thence to the terminals of a distant receiving station of the same character as the system of circuits shown in the figure terminating to the left of the line circuit 14.

Waves transmitted to station 1 from the distant station are conveyed over line circuit 14 through hybrid connections 12 over the receiving path 20 common to a plurality of west-going channels W₁, W₂, etc., and to the

filter or selective circuit 21 in channel W₁. Filter 21, which may be similar in type to filter 10, selects waves intended for the channel W₁ and excludes waves intended for other channels W₂, etc. connected to the common receiving path 20. The demodulator or the detector 22, labeled DM, connected to the output of filter 21 converts the modulated carrier wave for channel W₁ into a wave of signal frequency which is transmitted through the hybrid connections 3 and the line circuit 2 to the substation 1.

The power transmitted through each channel E₁, E₂, etc., is limited by a power limiter 5 individual to the modulating circuit included in said channel, so that in no instance may the amplitude or power of signals in any one channel be great enough to cause disturbances in an unrelated channel. Similarly, the total amount of power which it is possible to impress upon the repeater 15 common to all of the channels is limited to the sum of the maximum amounts of power transmitted over all the channels simultaneously. It is thus seen that the repeater 15 is never subjected to a load in excess of a fixed value and may, therefore, be operated as near as desired to its rated capacity without exceeding said capacity.

Although voice waves have been referred to in connection with the description of the invention, it is to be understood that any electric waves having similar characteristics to voice waves may be controlled in a similar manner and for the same purpose as described above in connection with voice waves.

The invention has been disclosed in connection with a specific circuit embodiment but the invention is not to be limited to the specific form of circuit shown. It is clear that various modifications of the means and methods disclosed are possible without departing from the novel features of the invention. The scope of the invention is more specifically defined in the appended claims.

What is claimed is:

1. In a multiplex carrier wave system, a plurality of communication channels, each of said channels including a circuit for transmitting modulating waves and a circuit for transmitting carrier waves modulated by said modulating waves, a common path for all of said channels, and means in each said first mentioned circuits to limit to a predetermined value, the power transmitted by said channel to said common path.

2. In a multiplex carrier wave system, a plurality of communication channels, each of said channels including a circuit for transmitting modulating waves and a circuit for transmitting carrier waves modulated by said modulating waves, a common path for all of said channels, a repeater in said common path, and means in each of said first men-

- tioned circuits to limit to a predetermined value, the power transmitted to said repeater.
3. In an electrical carrier wave system, the method of operation which comprises suppressing those portions of a modulating wave which are in excess of a predetermined value and modulating the carrier wave in accordance with the unsuppressed portion of said modulating wave.
- 10 4. In a multiplex carrier wave system comprising a plurality of channels having a common path, each including a circuit for transmitting modulating waves and a circuit for transmitting carrier waves modulated by said modulating waves, each of said channels containing frequency selecting means capable of discriminating against wave frequencies, below a given power value intended for said other channels, the method of operating 15 to prevent cross-talk in said common path due to waves having a power in excess of said given value which comprises suppressing portions of said modulating wave in excess of a predetermined value and modulating 20 said carrier wave in accordance with substantially the entire unsuppressed wave.
5. An electric relay having non-linear transmission characteristics whereby the out-

put of said relay is not proportional to the impressed input energy, means for supplying input energy thereto, and a power limiting device connected to receive energy from said means and to impress energy directly upon said relay, said power limiting device being capable of transmitting only energy 30 not in excess of the amount beyond which the output energy of said relay does not change.

6. In a carrier wave system, a circuit for transmitting modulating waves, a source of 35 carrier waves, a modulator for modulating carrier waves in accordance with said modulating waves, a transmission circuit for transmitting the resulting modulated waves, said circuit serving simultaneously for the 40 transmission of other waves and means for reducing interference between the waves transmitted over said circuit comprising means in said circuit transmitting said modulating waves for limiting the maximum amplitude of said modulating waves below a pre-determined valve.

In witness whereof, I hereunto subscribe my name this 28th day of December, A. D., 1922.

JOHN MILLS.
